UNITED STATES PATENT OFFICE.

WATSON ROSE AND WILLIAM H. ROSE, OF PHILADELPHIA, PENNSYLVANIA.

FIRE-DOOR.

SPECIFICATION forming part of Letters Patent No. 358,789, dated March 3, 1887.

Application filed July 13, 1886. Serial No. 207,875. (No model.)

To all whom it may concern:

Be it known that we, WATSON ROSE and WILLIAM H. ROSE, both of the city and county of Philadelphia, and State of Pennsylvania, have invented an Improvement in Fire-Doors, of which the following is a specification.

Our invention has reference to fire-doors for buildings; and it consists in certain improvements, all of which are fully set forth in the following specification and shown in the accompanying drawings, which form part thereof.

Heretofore great difficulty has been experienced in hanging the heavy doors required for this purpose. Short channel-iron sections were bolted to the brick-work or masonry; but the bolts were required to come so close together that the brick-work was insufficient to sustain the operation of the weighty door, and the bolts pulled through.

Hanging and sliding doors are well known in the art, as may be seen by an examination of the following Letters Patent, viz: No. 318,125, of 1885; No. 269,508, of 1882; No. 289,961, of 1883, and No. 321,518, of 1885. These constructions comprehend the support of the sliding door from a suitable rail, either of metal or wood; but in no case, as far as we are aware, has the specific construction herein set out been employed, the same being especially adapted to fire-doors for brick and stone buildings.

The object of our invention is to provide a construction capable of supporting the heaviest doors in use and overcome all of the present or existing objections.

In the drawings, Figure 1 is a front elevation of a fire-door embodying our invention, and Fig. 2 is a cross-section of same on line *xx*. A is the wall of the building, and may be made of brick-work or masonry.

B is the opening or doorway. The bottom of this doorway is provided with an iron floor-plate, C, extending slightly into the room and meeting the floor N, as at *c*, and is provided with a door guide-groove, D, arranged in the plane of the door K, the lower edge of which slides in said groove.

Secured to the wall above the doorway is the guide-rail E, from which the door K is hung by hangers or wheels M. The guide-

rail in length is preferably equal to twice the width of the door, so as to sustain it when open or closed, and is formed of two pieces, owing to the difficulty of casting ten-feet 55 lengths and maintaining the patterns against warping and formation of curved castings.

I is the guide-rail proper, upon which the door is hung, and is of small width. This rail is connected by base part H with the deep 60 plate G, which prevents warping of the rail and insures the door running uniformly at the same level, avoiding all binding in the lower guideway. By making the rear or sustaining plate, G, of great depth, its upper part will 65 extend above the guide-rail and allow of the long bolts L being inserted after the door-rail has been placed in position upon the wall, and will prevent cutting into the wall. This construction, owing to the fact that it prevents 70 warping in the patterns, and consequently in the castings, enables long or five-feet lengths to be made with facility, and does not require the bolts to come close together. This spreading of the bolts gives a more solid hold upon 75 the brick-work or masonry, and consequently makes the work more lasting and durable, and reduces the work of construction and setting, and hence the cost.

With the old form of rails the bolts required were brought so close together that often two bolts were sustained by the same brick, thus making the weakening apparent at a glance, and this weakness tended, by the constant movement of the heavy doors, to undermine 85 the strength of the wall above the doorway or in its weakest part. Our construction entirely overcomes all of these objections.

Having now described our invention, what we claim as new, and desire to secure by Letters 90 Patent, is—

1. In a fire-door for buildings, the combination of the wall with its doorway, the L-rail E, from which the door is hung, formed with the upwardly-extending rail-edge I, of small 95 depth, the horizontal base part H, and the upwardly-extending supporting-plate G, of great depth and made continuous throughout its length, long bolts considerably separated and extending through the plate G in a horizontal 100 plane considerably above the upper edge of the rail-edge I and secured upon the opposite

side of the wall, and a sliding door hung upon said rail-edge I, substantially as and for the purpose specified.

2. In a fire-door for buildings, the combination of the wall with its doorway, the L-rail E, from which the door is hung, formed with the upwardly-extending rail-edge I, of small depth, the horizontal base part H, and the upwardly-extending supporting-plate G, of great depth and made continuous throughout its length, long bolts considerably separated and extending through the plate G in a horizontal plane considerably above the upper edge of the rail-edge I and secured upon the opposite side of the wall, a sliding door hung upon said rail-edge I, and the floor-plate C, of metal, arranged in the doorway and having the groove D, for receiving the lower edge of the door,

substantially as and for the purpose specified.

3. A supporting and guide rail section for a fire-door, consisting of the horizontal base part H, having the upwardly-extending rail-edge I, of small depth, and the upwardly-extending supporting-plate G, of great depth and made continuous throughout its length, and having bolt-holes in the plate G in a line above the upper part of rail-edge I, substantially as and for the purpose specified.

In testimony of which invention we hereunto set our hands.

WATSON ROSE.
WILLIAM H. ROSE.
